UNITED STATES PATENT OFFICE.

OSCAR BERGSTROM, OF CHICAGO, ILLINOIS, ASSIGNOR TO HANDY MANUFACTURING COMPANY, OF CHICAGO, ILLINOIS.

VENEER-PRESS.

1,116,976.

Specification of Letters Patent. Patented Nov. 10, 1914.

Application filed November 10, 1913. Serial No. 800,167.

To all whom it may concern:

Be it known that I, OSCAR BERGSTROM, citizen of the United States, residing at Chicago, in the county of Cook and State 5 of Illinois, have invented certain new and useful Improvements in Veneer-Presses; and I do hereby declare the following to be a full, clear, and exact description of the invention, such as will enable others skilled 10 in the art to which it appertains to make and use the same.

This invention relates to improvements in screw jacks or the like, and particularly to the screws employed in veneer presses for 15 bringing pressure to bear upon veneer or laminated structures in the process of manufacture.

The particular object of the invention is to provide means whereby the screw may be 20 quickly adjusted to the position approximating that in which it is to be finally disposed and thereby effecting economy of time and labor.

In the accompanying drawings illustrating 25 a suitable embodiment of the invention, I have shown the latter applied to a veneer press for which the structure is particularly adapted, it being understood, of course, that the same may be embodied in screw jacks or 30 similar structures employing screw-shafts without departing from the invention.

In said drawings: Figure —1— is a fragmentary perspective view of a portion of a veneer press equipped with a screw embodying my invention. Fig. —2— is a fragmentary view in side elevation partly in section showing a screw shaft and the quick acting split nut engaging the same, and also the support for the frame carrying said nut. 40 Fig. —3— is an end elevation of the frame, the same being partly broken away and parts thereof shown in sections. Fig. —4— is a horizontal section partly in elevation on the line 4—4 of Fig. —2—. Fig. —5— is a 45 detail central longitudinal section on an enlarged scale of the lower end portion of the screw shaft showing a lever applied thereto for the purpose of rotating the same. Fig. —6— is a detail fragmentary plan view of 50 the lever employed for said purpose.

In veneer presses the screw shafts operate in exactly the opposite direction from the screw shafts of lifting jacks and the like, though obviously the principle and mode of 55 operation is substantially identical. In the

veneer press the screw shafts employed for compressing the veneer or the like upon the base of the press are suspended from supports joined to the base by means of a plurality of standards and moved downwardly 60 upon the load. The upper portion and base of the press are very heavy so as to enable them to be subjected to excessive separating strains without deflection, but such structures are outside of the scope of my invention which has for its sole object to provide means whereby the screw shafts may be readily raised and lowered without rotating the same after having performed their functions of maintaining the veneer under pressure and preparatory to bringing pressure upon a fresh batch of the same.

As shown in the accompanying drawings, at the upper portion 1 of an ordinary veneer press are secured two parallel channel 75 bars 2 between which is an open space 3 in which the shank of a screw shaft 4 is adapted to be received. The screw shaft has threaded engagement with a split-nut 5 disposed in a carriage 6 which is suspended by 80 means of flanges 7 from the flanges 8 of the channel bars 2. The lower end of the screw shaft is equipped with a rotatable bearing or presser foot 9 which is adapted to rest upon the load supported upon the base 10 85 of the press and remain nonrotatably engaged with said load while the screw shaft 4 is being rotated to compress such load. Contiguous to the lower end of the screw shaft 9 the latter is equipped with a pair 90 of parallel rigid annular flanges 11 each provided with projections similar to the teeth of a spur gear and which are adapted to permit ready engagement with said shaft of a wrench 12, illustrated in Fig. —6— of 95 the drawings. The upper collar 11 is further provided with projections 13 from which radial arms 14 project, the latter being adapted to be manually engaged for the purpose of preliminarily causing the presser foot 9 of the screw to bear upon the load to be subjected to pressure, the final pressure being applied by rotating said screw by means of said wrench 12.

The wrench 12 consists of a flat bar of 105 metal having a bifurcated end portion in which the hub carrying the flanges 11 is adapted to be received and engaged. Outwardly of said bifurcated end portion 15 the said bar is provided with two L-shaped 110

projections 16 disposed on opposite faces thereof and through the outer parallel arms of which a pin or shaft 17 passes, the latter passing also through the bar 12. Said pin or shaft 16 is adapted to engage in the recesses between contiguous teeth of said flanges 11 whereupon said bar or wrench may be employed to rotate the screw shaft 4 as will be obvious.

10 The carriage 6 comprises an upper flat wall 18 carrying said flanges 7 hereinbefore referred to, and which is provided with parallel vertical flanges 19 and 20, from the lower ends of which a sleeve 21 is suspended, the latter being equipped with a plurality of arms 22 secured at their outer ends to the lower edges of the flanges 19 and 20 by means of the machine screws 23.

Integral with the wall 18 and disposed above the same is a sleeve 24 axially aligned with said sleeve 21, the split nut 5 being disposed between said sleeve 21 and the wall 18 and thereby held against appreciable longitudinal movement relatively to the carriage 6. In said wall 18 below said sleeve 24 and in alignment therewith there is provided an elliptical opening 25 in which the upper contracted end portions of the members of said split nut 5 are adapted to move toward and away from each other to engage and release the screw-shaft 4. The latter passes freely through the sleeves 21 and 24 which, while permitting longitudinal movement of the screw shaft 4, serve to prevent lateral movement of the same. One of said members of said split nut 5 is provided between its ends with an internally threaded flange 26 in which the left-hand threaded portion 27 of a right and left threaded screw 28 engages, the latter being rotatably engaged with the flange 20 of the carriage or housing 6 through which it passes and being equipped at its outer end with a crank arm 29 for manually rotating the same. By means of the head 30 rigidly mounted on the outer end of said screw 28 and a collar 31 engaging the outer and inner faces respectively, of the flange 20 said shaft 28 is held against longitudinal movement relatively to said flange 20. Rigidly mounted in the other member of said screw shaft 5 are two parallel guide rods 32 passing freely through openings in the flanges 19 and 20 and also freely through openings 55 in the first-named member of said split nut 5. Rigid with said rod between the flange 20 and the contiguous member of the split nut 5 is a yoke 33 having a threaded opening in which the right-hand threads of said screw 28 engage, said yoke 33 being keyed to said rod 32 by means of the pin 34.

The operation of the device is as follows: When it is desired to move the screw shaft 4 to raise or lower the same the screw 28 is 65 rotated in a direction to cause the yoke 33

to move away from the flange 20. Rotation of said screw in this direction causes the opposing member of the split nut 5, with which said screw has threaded engagement, to move toward said flange 20. The movement of the yoke 33 is communicated to the farthest removed member of the split nut 5 thereby simultaneously moving said members of said split-nut in opposite directions and thus releasing the threads thereof from engagement with the threads of said screw shaft 4. The latter is maintained in its position by means of the sleeves 21 and 24 and after said members of said split nut have thus been separated may be easily raised and lowered. When raised one of the arms 14 is engaged with a hook 35 suspended from the sleeve 21 and thus said screw-shaft is supported by said hook when raised to substantially the upper limit of its movement. This is the position which the screw-shaft will normally occupy after being released from engagement with one load and preparatory to being engaged with the next succeeding load. After the next load has been mounted upon the base of the press the screw shaft is lowered by releasing the arm 14 from engagement with the hook 35 and usually said screw shaft is then permitted to move downwardly until its presser foot 9 rests upon the top of the load in the press. The shaft 28 is then again rotated in the opposite direction from that previously referred to by means of the crank arm 29 thereby moving the members of the split-nut 5 toward each other and bringing the threads thereof into engagement with the threads of the screw-shaft. This having been accomplished the screw-shaft may be turned manually by means of the arms 14 until the pressure exerted upon the load is greater than can be overcome by this manual operation. For further increasing the pressure on the load the wrench 12 is employed. The foregoing operation is repeated after each load has been held under pressure in the veneer press for the required period of time.

By means of my invention the operation of the press is rendered rapid compared to the present operation thereof. It enables all of the screws to be quickly lowered into position and manually operated to bring primary light pressure to bear on the load thus leaving a minimum of operation with the wrench 12 to be subsequently performed.

I claim as my invention:

1. In a veneer press or the like, pressure-actuating mechanism comprising a screw, a split nut for engaging said screw, a pair of horizontally disposed guides carrying both members of the said split nut, the said guides rigid with respect to one member of the said split nut and slidably with respect to the other thereof, a supporting member

housing the said nut and supporting the said guides, a member rigid with said guides, a right and left screw engaging the said member and one member of the said 5 nut and swiveled upon the said supporting member whereby to simultaneously move the nut members in opposite directions with respect to the first-named screw and the said supporting member.

10 2. In a veneer press or the like, pressure-actuating mechanism including a screw-shaft, a split-nut adapted to engage the same, a housing for said nut, axially alined sleeves on said housing receiving said 15 screw-shaft and permitting free longitudinal movement thereof, said nut disposed between said sleeves, a guide rod longitudinally movable in said housing in a direction perpendicular to the axis of said 20 sleeves and rigidly engaged with one member of said split nut and slidably engaged with the other member thereof, a right and left threaded screw having swiveled engagement with said housing and at its inner 25 end having threaded engagement with the other member of said split-nut, and a member rigid with said guide rod and having threaded engagement with the said screw, the respective right and left threads 30 of the latter engaging the respective parts for simultaneously moving the same in opposite directions and relatively to the housing.

3. In a veneer press or the like, pressure-actuating mechanism comprising a housing having smooth bore guide sleeves axially alined, a screw-shaft passing freely through said sleeves, a split-nut in said housing between said sleeves engaging said 40 screw-shaft, and means including a right and left threaded screw engaged with said housing and the respective members of said split nut for simultaneously moving the latter in opposite directions relatively to each 45 other and to the housing, thereby bringing the said split-nut into or out of engagement with the said screw-shaft according as the said screw is rotated in one or the other direction.

50 4. In a veneer press or the like, pressure-

actuating mechanism including a housing, a screw-shaft passing freely through smooth bore openings in opposite walls of said housing, a split-nut within said housing engaged therein for preventing axial 55 movement thereof relatively to the same, said nut engaging said screw-shaft, a right and left threaded screw having swiveled engagement with said housing, and operative connection between the respectively 60 right and left threaded portions of said screw and the respective members of said split nut for simultaneously moving the latter in opposite directions relatively to said housing as said screw is rotated. 65

5. In a veneer press or the like, the combination with a carriage, a screw passing slidably therethrough, and a separable split-nut housed in said carriage and adapted to be thrown into and out of engaging 70 relation to said screw, of a projection on the latter affording a handle for manually rotating the screw when the said split-nut is in engagement therewith, and means on said carriage adapted to engage said projection to support said screw when said split-nut is thrown out of engagement therewith. 75

6. In a veneer press or the like, the combination with a carriage, a screw passing 80 therethrough, and a separable split-nut housed in said carriage and adapted to be thrown into and out of engaging relation to said screw, of a laterally projecting arm on said screw contiguous to one end thereof, and a hook on said carriage adapted to engage said arm to support said screw when said split-nut is thrown out of engagement therewith, the said arm affording a handle for manually rotating the 85 screw when the said split-nut is in engagement therewith. 90

In testimony whereof I have signed my name in presence of two subscribing witnesses.

OSCAR BERGSTROM.
